UNITED STATES PATENT OFFICE.

WILLIAM S. MILLER, OF BIRMINGHAM, ALABAMA.

FIGURE WHEELED TOY.

Application filed May 2, 1923. Serial No. 636,169.

This invention relates to a toy of that type adapted to be drawn over the surface of the ground, one of the objects of the invention being to provide a wheel supported 5 jointed figure so mounted that during the forward movement thereof, a lateral "wiggling" or snake-like movement will be imparted to the figure.

With the foregoing and other objects in view which will appear as the description proceeds, the invention resides in the combination and arrangement of parts and in the details of construction hereinafter described and claimed, it being understood 15 that changes in the precise embodiment of the invention herein disclosed may be made within the scope of what is claimed without departing from the spirit of the invention.

In the accompanying drawings the preferred form of the invention has been shown.

In said drawings—

Figure 1 is a bottom plan view of the toy.

Fig. 2 is a side elevation thereof.

Fig. 3 is an enlarged section on line 3—3,

25 Fig. 2.

Referring to the figures by characters of reference, 1 designates the body of the toy, the same being made up of sections 2 hingedly connected at their ends as shown at 3. In 30 the structure shown, the front section 4 constitutes the head of the toy while the rear section 5 constitutes the tail. A pull cord 6 is adapted to be connected to a staple 7 or the like, attached to the top of the head 4. Secured to the bottom of the section next 35 to the head 4 is a metal strip 8, the ends of which are bent upwardly so as to be supported laterally beyond the sides of the section, the upper terminals of these ends 40 being offset inwardly as at 9 and fastened to the sides of the section. The sides of the strip 8 provide bearings for a short axle 10

and on the ends of the axle are eccentrically mounted supporting wheels 11 rotatable freely on the axle.

Another strip 8 similar to the one already described is secured to the bottom of the tail section 5 and is also provided with a short axle 10 on which are eccentrically mounted wheels 11.

It has been found that, by mounting the supporting wheels eccentrically, the toy when pulled forward, will be given a wiggling or snake-like motion, such motion being irregular and affording considerable 55 amusement.

Various means may be used for hingedly connecting the sections of the body. The preferred means is that illustrated in the drawings and includes a strip of fabric 12 60 extending longitudinally within the sections and providing flexible or hinged connections between the parts.

What is claimed is:—

A toy including an elongated body comprising sections hingedly connected for relative lateral swinging movement, strips secured to the bottoms of remotely spaced sections of the body, each strip being extended laterally beyond the sides of the section to 70 which it is attached, the ends of the strip being extended upwardly and thence inwardly and attached to the sides of said section, an axle extending through the upwardly extending portions of each strip and through the section to which the strip is connected, and wheels supporting the end portions of each axle, all of the wheels being of the same size and circular and each wheel being eccentrically mounted on its 75 axle.

In testimony that I claim the foregoing as my own, I have hereto affixed my signature.

WILLIAM S. MILLER.
